INVENTOR

Michael F. Brogan

UNITED STATES PATENT OFFICE.

MICHAEL F. BROGAN, OF LAWRENCE, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

LAST-BLOCK-PULLING DEVICE.

1,288,459.

Specification of Letters Patent. Patented Dec. 24, 1913.

Original application filed May 19, 1915, Serial No. 29,204. Divided and this application filed November 9, 1917. Serial No. 301,069.

To all whom it may concern:

Be it known that I, MICHAEL F. BROGAN, a citizen of the United States, residing at Lawrence, in the county of Essex and State 5 of Massachusetts, have invented certain Improvements in Last-Block-Pulling Devices, of which the following description, in connection with the accompanying drawings, is a specification, like reference characters on 10 the drawings indicating like parts in the several figures.

The present invention relates to devices for removing instep blocks from their lasts and this application constitutes a division of 15 my application Serial No. 29,204, filed May 19, 1915.

A large proportion of the lasts in present-day use are of the type having detachable instep blocks normally latched to the body 20 portion of the last. The instep block has a bore or hole therein extending from its face to the latch and aligned with the recess in the body of the last in which the plunger of the latch is seated. It is customary, before pulling the last from the shoe, for example, to detach the instep block and, as 25 previously practised, the shoe and last are held with one hand while a hook or bent rod held in the other hand is inserted in the hole in the block to release the holding latch, the hook being then pulled lengthwise of the shoe to pull the released block from the last.

This operation is time consuming, since 35 before the shoe can be subjected to the operation of the machine, such as a last pulling machine, the workman has to reach for the hand hook with one hand while holding the shoe with the other and after the instep 40 block has been released and pulled, to lay down the hook with the pulled instep block. Additionally, the lacing edges of the shoe must be spread apart to permit the insertion 45 of the hook and with one hand this is an awkward and time consuming operation. The use of the illustrated device saves the time required in reaching for and returning a hand hook and enables the operator to use 50 both hands in opening the lacing edges of the shoe to permit the latch releasing means to be inserted in the block bore.

A feature of the present invention consists in a device having a gripping member arranged to enter the instep-block bore of a last to disengage the block latch and automatically to grip and hold the block independently of a block latch for the separation of the block and the body of the last and the shoe. Advantageously, the gripping member is provided with a support 55 constructed and arranged to be attached to the frame of a machine designed to operate upon the shoe subsequently to the pulling of the instep block, such as the last pulling machine of my said application, or to any 60 suitable base or support, so that no time is lost in presenting the shoe to the machine, or in subjecting it to the desired operation, since the last and the shoe may be quickly 65 presented to the gripping member and immediately pulled away, the instep block remaining on the gripping member.

A further feature of the invention consists in a compressible block gripping member arranged for insertion in the block bore 75 to release the block latch and coincidentally and automatically to grip and hold the released block to permit separation of the block and the body of the last. As shown, compressible resilient gripping arms are 80 employed which arms are pressed together when inserted in the block bore to release the latch and act frictionally to grip the sides of the bore and to hold the released block while the shoe and last are pulled 85 away therefrom. A supporting standard is employed and is arranged detachably to hold the gripping member so that differently formed latch releasing members may be employed, if desired, for special types of instep blocks.

These and other features of the invention are described in detail in the following specification read in connection with the accompanying drawings, and are pointed out 90 in the appended claims.

In the accompanying drawings,

Figure 1 is a view in elevation of a device constructed in accordance with the present invention;

Fig. 2 is a similar view of the device attached to the frame of the last pulling ma-

chine of my application previously referred to;

Fig. 3 illustrates the block pulling device in juxtaposition to the instep block of a last within a shoe; and

Fig. 4 shows the gripping member after insertion in the block bore to release the latch and grip a block with the body of the last and shoe in the process of withdrawal 10 from the released block.

A supporting standard 4 preferably having its upper end 6 bent to form a bracket by means of which it may be attached to a suitable support is provided at its lower end 15 with a bore 8. In this bore is detachably held by means of a set screw 16 or other suitable means, a stem portion 10 at the rear end of the block releasing and gripping member. This member at its forward 20 end is split, forming spaced resilient spring arms 14 branching from an enlargement 12 intermediate the ends of the gripping member, which enlargement is intended to serve as a positioning stop and to engage the lower 25 end of the standard 4.

With the block gripping member suitably supported, as suggested, the workman may grasp a shoe, such as shown in Figs. 3 and 4, in both hands, spreading apart the lacing 30 edges of the shoe and presenting the shoe to the resilient gripping arms 14, so as to enter these arms in the bore 18 of the instep block 16 of the last. The lower edges of the arms are preferably beveled as shown, 35 so that as they are inserted within the block bore, they will be compressed. The last is forced upon the spring gripping arms until the latch 20 (Figs. 3 and 4) of the instep block is engaged by the end of the gripping 40 arms and depressed to release the instep block (Fig. 4), after which the shoe with the body of the last therein is withdrawn, the instep block remaining upon the resilient arms 14 which frictionally grip the sides 45 of the bore with sufficient force to support the block and permit the shoe to be withdrawn therefrom.

The shoe with the body of the last remaining within it, may now be presented to the 50 machine, such as the last pulling machine previously referred to, or may be subjected to any desired operation, without any attention being paid to the instep block. If the operation which is to be performed 55 upon the shoe is the pulling of the last from the shoe, the withdrawn instep block will be found conveniently positioned for reattachment to the body of the pulled last.

Having thus described my invention, what 60 I claim as new and desire to secure by Letters Patent of the United States is:—

1. Means for pulling instep blocks from lasts comprising compressible gripping arms arranged to enter the instep block 65 hole to disengage the block latch and to hold

the released block, with a supporting standard connected to and extending from said arms.

2. Means for pulling instep blocks from lasts comprising a standard, and compressible 70 spring arms extending from said standard and arranged to enter the instep block hole to disengage the block latch and to hold the released block.

3. Means for pulling instep blocks from 75 lasts comprising a standard having a socket therein, and a member detachably secured in said socket and having spring arms normally spread apart and extending from said standard, said arms being compressible 80 to enter the instep block hole to disengage the block latch and frictionally to grip and hold the released block.

4. Means for pulling instep blocks from 85 lasts comprising a gripping member arranged to enter the instep block hole to disengage the block latch and constructed automatically to grip and hold the released block for separation of the block and last, and a support for said member constructed and 90 arranged for attachment to a suitable base.

5. Means for pulling instep blocks from 95 lasts comprising a gripping member arranged to enter the instep block hole to disengage the block latch and to hold the released block upon separation of the block and last, with a stationary support for said gripping member.

6. A last block pulling device having a compressible gripping member arranged to 100 enter the bore in the instep block of a last to release the block latch and constructed, when so inserted, to be compressed and automatically to grip and hold the released block for the separation of the block and last body. 105

7. A last block pulling device having a gripping member arranged for insertion in the bore in the instep block of a last to release the block latch, said member being constructed and arranged, when so inserted, 110 automatically to grip and hold said block independently of the block latch for the separation of the block and last body.

8. A last block pulling device having a compressible gripping member arranged for 115 insertion in the bore of the instep block of a last to release the block latch, said member being constructed and arranged for compression by said insertion automatically and frictionally to grip and hold the released 120 block for the separation of the block and last body.

9. A last block pulling device having a gripping member arranged for insertion in the bore of the instep block of a last to release the block latch, said member being constructed and arranged, when so inserted, 125 automatically to grip and hold said block independently of the block latch for the separation of the block and last body, and a 130

support for said member constructed and arranged for attachment to a suitable stationary base.

10. A last block pulling device having a latch releasing spring arms arranged to be compressed by insertion in the bore of the instep block of a last frictionally to grip and hold the instep block for the separation of the block and last body.

11. A last block pulling device having a latch-releasing split finger of resilient material compressible by latch-releasing insertion in the bore in the instep block of a last frictionally to grip and hold said instep block for the separation of the block and last body.

12. A last block releasing device comprising a standard adapted for attachment to a suitable support and having detachably secured thereto a gripping member arranged

for insertion in the bore in the instep block of a last to release the block latch and constructed, when so inserted, to grip and hold said block for the separation of the block and last body.

25

13. A last block pulling device provided with compressible arms arranged to be forced into the bore in the instep block of a last to release the block latch and frictionally to grip and hold the released block.

30

14. A last block pulling device provided with a split finger of resilient material having beveled ends and arranged to be forced into the bore in the instep block of a last to release the block latch and coincidentally to compress said split finger frictionally to grip and hold the released block.

In testimony whereof I have signed my name to this specification.

MICHAEL F. BROGAN.
